UNITED STATES PATENT OFFICE.

DAVID H. COLES, OF NEW YORK, N. Y.

COMBINED BRAIDING AND CORDING ATTACHMENT FOR SEWING-MACHINES.

SPECIFICATION forming part of Letters Patent No. 318,357, dated May 19, 1885.

Application filed January 29, 1885. (No model.)

To all whom it may concern:

Be it known that I, DAVID H. COLES, a citizen of the United States, residing at New York, in the county and State of New York, 5 have invented new and useful Improvements in Combined Braiding and Cording Attachments to Sewing-Machines, of which the following is a specification.

This invention consists in a presser-foot 10 provided with a needle-hole extending transversely through it, and two independent longitudinal channels, one above the other and in advance of the needle-hole, said channels being separated by an intervening longitudinal 15 partition, forming a part of the presser-foot, and which terminates in advance of the needle-hole; also, in a presser-foot provided with a needle-hole extending transversely through it, a braid-guide situated in advance 20 of the needle-hole and centrally in regard to the same, and a cord-guide situated above the braid-guide and eccentrically in regard to the needle-hole.

In the accompanying drawings, Figure 1 25 represents a perspective view of my attachment. Fig. 2 is a longitudinal section of the same. Fig. 3 is an end view of the same. Fig. 4 is a diagram showing the relative positions of the braid, the cord, and the needle.

30 Similar letters indicate corresponding parts. In the drawings, the letter A designates the presser-foot of a sewing-machine, which is provided with the needle-hole *a*, extending transversely through it, and with two longitudinal channels, *b* *c*, one above the other and in advance of the needle-hole, said channels being separated by an intervening longitudinal partition forming a part of the presser-foot, and which terminates in advance of the needle- 35 hole, thereby constituting independent and accurate guides for the braid and cord. The channel *b* forms the braid-guide and the channel *c* the cord-guide; but the last-named channel may also be used as a guide for an addi- 40

tional braid narrower than the braid passing 45 through guide *b*, so that either a cord and a braid or two braids, one above the other, can be sewed on a garment simultaneously by the same needle. The braid-guide *b* is by preference placed centrally in regard to the needle-hole, while the cord-guide *c* is placed eccentrically in regard to the needle-hole, so that the needle in its downward movement passes through the side of the cord *d* and through the middle of the braid *e*, as indicated in Fig. 50 4. When the stitch is drawn tight, the cord rolls over to the middle of the braid, so as to conceal the stitch. If the cord-guide is placed centrally in regard to the needle-hole, the 55 stitch will be visible throughout the entire length of the cord, and the appearance of the work will be impaired.

It is obvious that my presser-foot can be so constructed that it is applicable to almost all kinds of sewing-machines.

60 What I claim as new, and desire to secure by Letters Patent, is—

1. The presser-foot provided with a needle-hole extending transversely through it, and two independent longitudinal channels, one 65 above the other and in advance of the needle-hole, said channels separated by an intervening longitudinal partition forming a part of the presser-foot and terminating in advance of the needle-hole.

2. A presser-foot provided with a needle-hole extending transversely through it, a braid-guide situated in advance of the needle-hole and centrally in regard to the same, and a cord-guide situated above the braid-guide 70 and eccentrically in regard to the needle-hole.

In testimony whereof I have hereunto set my hand and seal in the presence of two subscribing witnesses.

DAVID H. COLES. [L. S.]
